Primary Examiner — Keli L Hill*Assistant Examiner* — Harold E Blackwell, II(74) *Attorney, Agent, or Firm* — Joseph T. Leone, Esq.; DeWitt LLP(57) **CLAIM**

The ornamental design for a door jam, as shown and described.

DESCRIPTION

FIG. 1 is a top-right perspective view of a door jam showing my new design;

FIG. 2 is a right side perspective view thereof;

FIG. 3 is a right side elevational view thereof; the left-side elevational view is a mirror image thereof;

FIG. 4 is a top plan view thereof; and,

FIG. 5 is a front elevational view thereof; the bottom plan view and the rear elevational view thereof being identical thereto.
